UNITED STATES PATENT OFFICE.

FREDERICK YOUNG, OF CELORON, NEW YORK.

CURTAIN-FIXTURE.

1,128,396.

Specification of Letters Patent.

Patented Feb. 16, 1915.

Application filed April 18, 1914. Serial No. 832,818.

To all whom it may concern:

Be it known that I, FREDERICK YOUNG, a citizen of the United States, residing at the village of Celoron, in the county of Chautauqua and State of New York, have invented certain new and useful Improvements in Curtain-Fixtures, of which the following, taken in connection with the accompanying drawings, is a specification.

10 The invention relates to combination window shade and curtain pole supports; and the object of the improvement is to provide a simple and strong curtain and shade support which may be attached to the window 15 casing without the use of attaching screws and which is adjustable to different length shade rollers; and the invention consists of the novel features and combinations herein-after set forth and claimed.

20 In the drawings, Figure 1 is a perspective view of the upper end of a window frame with the curtain fixtures attached thereto at each side, the frame and roller being broken away through the central portion. Fig. 2 is a perspective view of one 25 of the detached curtain fixtures. Fig. 3 is a sectional view of the window casing below the curtain fixture, showing a plan view of the curtain fixture as attached to said 30 window casing. Fig. 4 is an end elevation of the curtain fixture, also showing the edge of the window casing, the fixture being attached to said window casing. Fig. 5 is an elevation of the rear side of the fixture.

35 Like numerals of reference refer to corresponding parts in the several views.

The numeral 10 designates the wall, and the numeral 11 the window frame. Many window frames are finely finished and it is 40 desirable not to mar or mutilate said frame.

The curtain fixtures 12 and 13 are constructed so as to be detachably attached to the window casing 11 without marring or defacing the same in the following manner:

45 The main plates of the fixtures 12 and 13, which are for the right and left sides of the window casing 11, are each made from a single piece of sheet metal having the rearward turned lugs 14, 15 and 16.

50 The lugs 15 and 16 have inturned points 17 to engage the edges of the window casing 11. A screw 18 is provided in the lug 14 with a threaded opening therethrough and a toothed or padded clamping piece 19 55 is attached to the inner end of the screw 18 so that when desired the teeth 20 may en-

gage the edge of the window casing 11 so that by turning the screw 18 the toothed lugs 15 and 16 are forced to engage the outer edge of the casing 11 thereby holding the fixture firmly upon said casing, yet permitting it to be quickly removed by the simple withdrawal of the pressure by the screw 18.

For certain fine finished surfaces, however, it is preferred not even to have the small points 20 engage the surface of the window frame 11. Accordingly a pad 34 is attached to the plate 19, the points 20 aiding in holding the pad 34 in place thereon. Said pad 34 may be made of any material which will give a frictional hold on the surface of the window frame 11 without marring the same. For this purpose felt, rubber, leather or any similar strong, yet slightly resilient material, may be used. The outer edge of the window casing 11 is not so noticeable, hence it is rare that pads are necessary. Pads 35, as shown in dotted line in Fig. 5, may be attached to the lugs 15 and 16, however, without departing from my invention, and it is apparent that the two pads 34 and 35 will clamp the most delicate polished surfaces without materially injuring the same. It is found that comparatively little pressure of the screw 18 85 on the clamping surfaces holds the plates 12 and 13 firmly in position against the downward draw of the shade on the shade roller 26 and the curtains on the pole 31.

The fixtures 12 and 13 may be made in any desired design but are preferably cut away at 21 so as to provide the lug 14 on the lower edge and to form on the upper edge a strip having return bend edges to form a slide 22 to receive therein the metal strip 23 with its outwardly turned end 24 having the opening 25 in said outwardly turned end to receive the end of the shade roller 26. The opposite end 27 of the strip 23 is narrowed so as to engage the holes 28 100 and thereby adjust the strip 23 to any desired length of shade roller 26.

The upper portion of the sheet metal plate is cut to form an outwardly turned supporting strip 29 for the curtain pole, which 105 is formed on its outer end with an upwardly opening curve 30 to receive one end of the curtain pole 31 therein. A bracing strip 32 is riveted to said outwardly extending strip 29 near the outer end and to the lower 110 edge of the sheet metal plate, thereby forming a strong support for the curtain pole 31.

The plate 12 or 13 may be bent also to accommodate molding or other projections on the face of the casing 11, as shown at 33.

It is obvious that the fixtures 12 and 13 5 may be made practically the same for the right and left sides of the window casing, that they are simple and cheap, being easily stamped out by suitable dies and form strong and durable supports for the shade 10 roller 26 and curtain pole 31.

I claim as new:—

1. A curtain fixture comprising a plate, means for attaching said plate to the window frame, a slide on said plate, a strip 15 slidably mounted in said slide and one end thereof extending out to support one end of a shade roller, said plate having a series of holes in line with the other end of said sliding strip, said other end turned to fit in one 20 of said series of holes and thereby adjust the position of said strip by springing into the same.

2. A curtain fixture comprising a plate, means for attaching said plate to the window frame, a strip integral with said plate 25 at one end and bent outwardly therefrom to form a curtain pole support, and a brace attached to said plate at one end and to said outwardly turned strip at the other to support the same.

3. A curtain fixture comprising a plate, rearwardly turned toothed lugs on said plate for engaging the outer edge of the window frame, a rearwardly turned lug for 30 the inner edge of the window frame, a screw mounted in a threaded opening in said rear-

wardly turned lug for the inner edge of the window frame and a toothed plate on the inner end of said screw for engaging the inner edge of the window frame, a slide on 40 said plate, a strip slidably mounted in said slide, one end of said strip turned outwardly to support one end of a shade roller, the other end of said strip tapered and turned toward said plate, said plate having a series of holes in line with the turned end of said sliding strip to adjustably receive and hold the same.

4. A curtain fixture comprising a plate, rearwardly turned toothed lugs on said 50 plate for the outer edge of the window frame, a rearwardly turned lug for the inner side of the window frame, a screw clamp mounted in a threaded opening in said rearwardly turned lug for the inner 55 side of the window frame, an angular strip slidably mounted on said plate to form an adjustable support for one end of the shade roller, a strip cut from the upper edge of said plate and integral therewith, said strip turned outwardly to form a curtain pole support, and a bracing strip attached to the under side of said outwardly turned strip and to said plate to support the outer end of said strip.

In testimony whereof I have affixed my signature in the presence of two witnesses.

FREDERICK YOUNG.
